TREEING MACHINE COMPANY, OF BROCKTON, MASSACHUSETTS, A CORPORATION OF
MAINE.

TREEING-MACHINE.

1,030,810.

Specification of Letters Patent. Patented June 25, 1912.

Application filed September 16, 1902. Serial No. 123,639.

To all whom it may concern:

Be it known that I, JOHN S. HANSEN, a citizen of the United States, residing at Medford, in the county of Middlesex and 5 State of Massachusetts, have invented certain Improvements in Treeing-Machines, of which the following description, in connection with the accompanying drawings, is a specification, like reference characters on 10 the drawing indicating like parts in the several figures.

This invention relates to machines for treeing boots and shoes, and more particularly to machines of the type shown in 15 United States Letters Patent No. 442,034, dated Dec. 2nd, 1890, in which a pair of trees is supported on an oscillatory head and the trees are alternately brought into operative position with relation to an actuator, 20 shown as a lever, which expands the trees to distend the shoes to the shape which they possessed when removed from the lasts, and to stretch the shoes slightly. Any form of expansible trees may be used in this machine, but I have shown trees of the type disclosed in the patent to Tyler No. 319,356, granted June 2, 1885, which are expanded by a cam connected to a draft rod, which when drawn upwardly in the tree leg sepa- 25 30 rates the heel from the fore part of the tree. A returning spring moves the rod and cam to restore the parts of the tree to their contracted position. While on the expanded tree the shoe is usually subjected to rubbing 35 and ironing with a heated or other instrument, to assist in bringing the shoe into its original shape, and to remove from it the wrinkles and creases that were formed during previous steps in its manufacture. The 40 ironing operation polishes the shoe upper and gives it a better appearance than it would otherwise have. Sometimes also the shoe is treated to one or more applications of dressing or finishing material while on 45 the tree.

One very important feature of my invention consists in providing a treeing machine with means for moving a tree to present it at a given point, as for instance in front of 50 the workman who performs the rubbing or ironing operation or applies the dressing, or in operative position with relation to a mechanism which is to expand the tree or to perform some operation upon the shoe car-

ried by the tree. In connection with this 55 feature of my invention I have also provided means for removing a tree from such operative position after the tree has been expanded or the operation on the shoe has been completed. By reason of these im- 60 provements the manual labor heretofore required for moving the tree to and from desired position is rendered unnecessary.

Another important feature of my invention consists in providing a machine having 65 a plurality of trees with mechanism for moving said trees to present them successively at a given point, whereby the capacity of the machine is increased and the labor involved in its operation is reduced. 70

Heretofore when a machine having a plurality of trees has been employed, it has been necessary for the workman to travel from one tree to another or to move the trees manually to bring them successively to the desired position, either of which procedures involves labor and consumes time. Means is also provided for securing a tree against lateral movement while in position to be operated upon and a further feature of this 80 invention consists in novel means for actuating the securing means or latch by which the tree is held in operative position.

In the embodiment of the invention herein shown the latch is actuated to release the 85 tree by an actuator which is operated by the return stroke of the expanding lever so that a separate operation is not required for this purpose. As shown the actuator and the latch move together until the tree has been 90 released and the latch and actuator also move relatively so that after the release of the tree has taken place the latch and actuator will be disengaged. It will of course be understood that this means for operating 95 the latch or similar part may be employed in various other connections than that herein explained and that the invention is not limited to the use of this means in the machine shown.

In connection with the means for releasing the tree to permit it to be moved aside, I have provided automatic means for moving said tree out of operative position as soon as it is released, and for bringing another tree 105 within reach of the workman, so that he can, if desired, manually move said latter tree into position to be secured and operated

- upon without leaving his position. This means is herein shown and described as used in connection and coöperation with the mechanism above referred to for presenting the tree feet successively in the desired position, but its use is not, of course, limited to such a combination, as this feature of my invention may be used independently if desired.
- 10 A further important feature of my invention consists in providing a machine in which a manually controlled mechanism, which has heretofore been employed in treeing machines, shall, in addition to its usual function, automatically move the trees to present them successively at the desired point. This arrangement results in effecting the additional operation by a mechanism which has been present in the prior machine, thus avoiding the necessity for another operating mechanism.
- 15 Another feature of my invention consists in providing a treeing machine which comprises a tree-carrier, an expansible tree, and an actuating mechanism for causing the expansion of said tree, with a connection between said actuating mechanism and the tree-carrier, by means of which said tree is presented automatically to the actuating mechanism for the purpose of being expanded, and is moved into a different position after it has been expanded by the actuating mechanism.
- 20 The machine is equipped with locking means for maintaining the trees in expanded condition so that the shoe may remain on the tree and "set" after the treeing operation has been performed and after a coat of dressing has been applied, if the shoe is dressed while on the tree. The expanded tree is moved away from the workman and allowed to stand while another shoe is applied to another tree of the machine and while said latter tree is expanded and the treeing operations are performed on the shoe carried by it. The tree first acted upon is then returned to operative position, and I have provided automatic means for unlocking said tree so that it may be presented to the workman in collapsed condition ready to have the shoe removed from it. In certain classes of work, however, a second coat of dressing is to be applied before the shoe is removed from the tree, or some other operation is to be performed on the shoe, and at such times it is undesirable to have the tree collapsed when it is returned to operative position, because it would have to be again expanded in order to be in condition to be operated upon. I have therefore arranged the automatic unlocking means so that it can be removed or can be rendered inoperative at the will of the workman to discontinue the automatic unlocking of the trees as they are returned to operative

position. This permits the tree to be presented repeatedly in position to have the shoe carried thereon treated before the tree is collapsed.

70 In all prior machines known to me in which the trees have been movable forth and back with relation to the position of the workman, instead of the workman traveling from one tree to the other, the means for holding the tree in expanded condition has been released and the tree contracted at or before the time when the tree was returned to its operative position in front of the workman, and when it was desired to apply a second coat of dressing to the shoe before removing it from the tree, the workman was obliged to expand the tree again before applying the dressing. This objection has been overcome by my invention in which the means for unlocking the tree may be rendered inoperative when desired. I have also provided means under the control of the workman for releasing the lock and permitting the tree to be collapsed whenever desired.

75 80 85 90 95 100 105 110 115 120 125 130

In the machine herein shown two trees are employed and for the best results these trees are shaped one for right, and the other for left, shoes. In practice it occasionally happens that several shoes which are all rights or all lefts are to be operated upon in succession, as, for instance, when shoes are returned for a second treeing operation, and it is desirable then to use the proper tree, either the right or the left one, several consecutive times. I have therefore provided for rendering inoperative the mechanism for withdrawing the securing means which retain the tree against lateral movement and also for rendering inoperative the mechanism for moving the trees forth and back to operative position when it is desired to employ only one of the trees in treeing several shoes in succession.

These and other features of my invention, including certain details of construction and combinations of parts, will be explained in detail in the accompanying description and pointed out in the claims.

Figure 1 is a side elevation of the machine with certain parts broken away. Fig. 2 is a side elevation of the lower portion of the machine with the parts in a different position from that shown in Fig. 1. Fig. 3 is a plan view of that lower portion of the machine shown in Fig. 2. Fig. 4 is a plan view partly in section, of the upper portion of the machine and with certain portions broken away. Fig. 5 is a view of a portion of the machine shown in Fig. 1, with the parts in a different position. Fig. 6 is a side elevation of an intermediate portion of the machine, showing in inoperative position the mechanism for moving the tree laterally.

A indicates an upper table supported upon legs B. Said legs also support a lower table A'. The upper table A has secured on it a bracket C in which a vertically arranged rockshaft 9 has bearings. The rockshaft 9 has secured thereto, by the clamping screw α , a head 10 which rests on a ball bearing E on the bracket so that the head may be turned freely by the rockshaft. 10 The head is provided in this instance with two radially projecting arms or branches 11, 12, which form bearings for the trunnions d' of the shoe trees D. The arms 11 and 12 are counterparts of each other and the trees are 15 also alike. It will therefore be necessary to describe only one tree and its relation to its supporting arm and to the operating mechanism. The construction of one of the trees D is clearly disclosed in Fig. 4, and 20 such tree will be described with relation to its supporting arm 12.

The expandible tree herein shown comprises a front and a rear section which are moved toward and from each other, to expand and contract the tree, by a rod d⁴, which is adapted to be drawn out to expand the tree by a suitable actuator shown as a lever 40, hereinafter described, and to be returned to normal position to contract the 30 tree by a spring d⁵. The rod is guided in a loop d⁶ secured to the forepart of said tree, and is provided with shoulders d⁷ which serve as stops to limit the inward movement of the rod as it is returned to position to 35 contract the tree. The trunnion d' of the tree is held in the bearing of its supporting arm by means of a set screw d⁸ extending through the bearing into an annular groove d⁹ in the trunnion of the tree, as shown in 40 Figs. 1 and 4. The supporting arm is hollow, as shown in Fig. 4. The rod d⁴ is surrounded in the hollow portion of the arm by a heavy coiled spring 15, which bears at the rear end against an adjustable collar 16, the 45 position of which may be altered by the hand nut 17 and check nut 18, shown in Fig. 4. The rod d⁴ receives a follower 20 in front of the spring 15. The follower is provided with a downwardly projecting lug 50 21 which extends through a slot in the supporting arm, and is provided with a guide pin 22 which extends through suitable recesses in depending lugs 10^a, 10^b of the head, as seen in Figs. 1 and 4.

55 For the purpose of locking the tree so that it shall remain expanded after the actuating lever is retracted, duplicate mechanisms are provided, one on each of the branches 11 and 12 of the machine head 10. 60 It will be necessary to describe only one of these mechanisms, reference being had particularly to Fig. 4. 24 indicates a latch connected to the head by the pivot pin 25 and held normally in the position shown in Fig. 65 4 by a spring 27 connecting it to the similar

latch on the branch 12 of the head. The latch 24 has a shoulder 26 to interlock with a coöperating shoulder 23 on the lug 21 depending from the follower 20 of the tree. The tree is expanded by the actuator 40, 70 which to this end engages the lug 21 and moves it until it reaches the position for the shoulders 23 and 26 to interlock, after which the tree is held by said shoulders in expanded condition until the shoulders are disengaged. 75 The position of the parts when the tree is locked in expanded condition is shown in Fig. 5. After the tree has been locked it is moved laterally away from the actuating lever, as will be described, and is subsequently returned to the actuating lever. For the purpose of unlocking the tree automatically to permit it to collapse when it is returned to operative position with relation to the actuating lever, the latch 24 is 80 extended beyond the shoulder 26 and is provided with a head having the face 29 and also the faces 30 and 31, which latter are beveled as shown in Fig. 4. 33 indicates a stop or abutment on the head of the lever 40 and located in the path of the face 29 of the latch head as the tree is moved into position in front of the lever. The contact of the latch with the abutment 33 turns the latch far enough for disengaging the shoulder 26 from the shoulder of the tree lug 21 to unlock the tree and permit it to be collapsed by its returning spring d⁵ before mentioned. 95

As hereinbefore explained, it is desirable 100 in some classes of work to apply a second coat of dressing or to perform some other operation on the shoe before removing it from the tree, and in such instances it is better to have the tree remain in expanded 105 condition when it is returned to position to be operated upon. I have therefore mounted the stops 33 which cause the automatic collapse of the trees so that they can be rendered inoperative or can be removed 110 from the machine when it is not desired to use them. As herein shown the stops are posts secured by set screws 34 in recesses in the head of the lever, and if it is not desired to collapse the trees when they are returned to operative position, these stops may 115 be adjusted below the plane of the latches or may be removed. 35, 35, indicate other stops or abutments on the head of the lever 40 by which the latches may be moved to 120 unlock the tree when the stops 33 are not used. The stops 35 are in advance, that is, to the left as seen in Figs. 1, 4, and 5, of the stops 33 in position to engage the beveled face 30 of the latch head, and thereby 125 rock the latch to release the lug 21 of the tree when the head of the lever 40 is moved slightly to the right as seen in said figures.

The mechanisms above described for locking the tree in expanded condition and for 130

unlocking the tree either automatically as the tree is moved into position to have the shoe on it removed, or at the will of the workman subsequent to its having been moved into such position, is shown in the drawings in connection with a mechanism for moving the trees to and from their operative positions, but I desire it to be understood that my invention is not limited to the use of these mechanisms together, as it is clearly within the scope of the present invention to use either of these mechanisms without the other.

The rockshaft 9, to the upper end of which is secured the head 10, carrying the trees, also supports a cam plate 50 by means of which the shaft 9 is rocked to remove one tree from position in front of the actuator 40 and present the other tree in such position. The plate is provided on its upper face with cam surfaces 52, 52, separated by a depression 54, as shown in Figs. 1, 2 and 3.

60 indicates a cam operating arm pivotally connected to the bell-crank lever 43 near its upper end at 62. The arm is provided at its rear end with a cam roll 64 to engage the cam surfaces 52 of the plate 50.

70 indicates a spring secured to the lower arm of the bell-crank lever 43 and connected at its other end to the table at 72, as shown in Fig. 1. The arrangement is such that, when the bell-crank lever is moved from the position shown in Fig. 1 to the position shown in Fig. 2, for causing the expansion of the tree, the spring 70 is put under tension and acts to return the lever 43 to normal position when permitted to do so. When the lever is returned from the position shown in Fig. 2 to the normal position shown in Fig. 1, the cam operating arm 60 on the upper end of the lever is carried against one of the cam faces 52 of the cam plate on the rockshaft and, by reason of the inclination of the cam face to the path of travel of the arm 60, as shown most clearly in Fig. 3, the cam plate is moved laterally in the direction of the arrow, Fig. 3, thus turning the rockshaft and moving the head 10 to carry the tree last expanded away from the actuator 40 and to present the other tree to said actuator. In this movement of the cam plate 50, the roller 64 on the arm 60 travels in contact with the cam surface 52 until it reaches the depression 54 which it enters, and then it rides up the wall of said depression and slides over the adjoining cam surface, as shown in dotted lines in Fig. 3, the momentum of the parts causing the completion of the movement of the rockshaft after the roll leaves the cam face and enters the depression 54.

When the tree which has been brought into position in front of the actuating lever is expanded by the depression of the foot-piece of the bell-crank lever 43 against the

tension of the spring 70, the arm 60 will be withdrawn from above the cam 52 and assume a position in front of said cam, ready to contact with the cam when the returning spring 70 is permitted to act and thereby turn the plate 50 and the rockshaft in the opposite direction to that in which they were before moved.

For the purpose of securing the trees in operative position in front of the lever 40, the table A is provided with a forked bracket 90, see Figs. 1 and 4, between the forks 92, 92, of which is pivoted at 94, a latch or lever 80. The lever is guided and braced against lateral strain by the forks 80 of the bracket, and is provided with a notched head 82 adapted to receive a lug d^{10} with which each of the arms 11 and 12 of the tree-carrying head 10 is equipped. When the lug d^{10} is within the notch of the head of the securing lever the tree is firmly held against lateral movement during the rubbing and ironing operations which may be performed on the shoe being treed. The securing lever 80 is held normally in position to embrace the lug d^{10} and secure a tree against lateral movement by a spring 84 connecting the lower arm of the lever with the table A. The securing lever is moved in opposition to the spring 84 at the proper time, to release the lug d^{10} and permit the tree to be moved laterally, by an actuator herein shown as a tripping device 100 operated by the bell-crank lever 43.

102 indicates a carrier one end of which is pivotally connected to the lever 43 at 40° , while the other end is removably suspended in a hanger 104 which depends from the table A, and through which the carrier may slide as it is moved by the lever 43, see Fig. 1. A block 106 is adjustably secured on the carrier and the tripping device 100 is pivotally connected to the block. The tripping device has a tail-piece 103 which extends downwardly and contacts with the block 106 below and back of the pivotal connection of the device thereto. The tail-piece acts as a stop to hold the tripping device normally in a horizontal plane, but permits it to be turned upwardly. The tripping device has at its free end a shoulder 100^a, and the latch or securing lever 80 has a similar shoulder 80^a located in the same horizontal plane and in the path of the shoulder on the tripping device as said device is moved by the lever 43.

The normal position of the tripping device 100 and its associated parts is shown in Fig. 1. When the lever 43 is depressed to move the actuator 40 and expand a tree, the tripping device and the cam actuating arm 60 are moved into the position, relative to the co-operating parts, which is shown in Fig. 2. When the returning spring 70 is permitted to act for moving the lever 43

back toward normal position, the shoulder 100^a of the tripping device contacts with the shoulder 80^a on the securing lever and rocks the head of said lever to the left, viewing 5 Fig. 1, thereby releasing the lug d^{10} .

It will be seen from Fig. 2 that when the lever 43 is in its depressed position the roll 64 on the cam operating arm 60 stands back some distance from the cam surface 52. In 10 the return movement of the lever the tripping device strikes the lever 80 and releases the tree, and thereafter the roll 64 strikes the cam surface 52 and turns the rock-shaft to move the trees laterally and carry the 15 next tree to be operated upon into engagement with the head 82 of the securing lever.

The tripping device and the securing lever move about different centers such that their shoulders 100^a and 80^a travel in diverging paths, as indicated in Fig. 2, and the securing lever is therefore disengaged automatically from the tripping device after it has been moved a short distance, sufficient to release the lug d^{10} , and said lever is then 25 permitted to be returned to its normal position by its spring 84 in time to receive and secure the companion tree which, it will be understood, is moving toward the securing lever at the same time that the released tree 30 is moving away. The period of engagement of the shoulders can be varied by adjusting the block 106 on the bracket 102. While the tripping device 100 for actuating the latch is shown as reciprocating in a curved path 35 and the latch is shown as swinging in a curved path, it is not essential to the invention that either of said parts move in a curved path.

66, 66, indicate spring-pressed plungers 40 secured to the legs B, B, and 56 indicates a lug formed on the cam plate 50 and which is arranged to engage one or the other of the spring plungers when either of the trees is in operative position in front of the actuator 40. The spring plungers serve two 45 purposes. They act as yielding buffers to arrest the movement of the cam plate and they also exert a constant pressure on the cam plate, tending to turn the rockshaft to 50 move the tree that is in operative position away from such position. The rockshaft turns very freely in its bearings and the force of the springs which actuate these 55 plungers is sufficient so that they unaided, would carry the tree last operated upon away from the securing device 80 and cause 60 the tree next to be operated upon to be brought within reach of the workman. This pressure becomes effective the instant that 65 the locking lever 80 is moved far enough to release the lug d^{10} , and the lug is thus moved out of alinement with the notch in the head of the locking lever before said lever is returned to locking position. The plungers 65 give the cam a movement, yieldingly en-

forced, prior to the positive movement imparted to the cam by the arm 60 on the lever 43.

I have shown the machine as provided with the spring plungers 66, one of which gives the rockshaft a movement for carrying the tree last operated upon away from the securing device 80 and bring the other tree within reach of the workman without requiring him to move, and also with the 75 cam-operating arm 60 on the lever 43, which engages a cam surface 52, after the spring plunger has imparted to the rockshaft its initial impulse, and thereby accelerates the rockshaft enough to cause it to complete its 80 movement for bringing the tree next to be operated upon into operative position, thereby pushing back the other plunger 66 into position to act the next time the rockshaft is to be oscillated. While for the best 85 results I prefer to use these mechanisms in combination, it is to be understood that either of these mechanisms alone is useful in a treeing machine, and my invention in its broadest aspect is not limited to their 90 use together but contemplates a treeing machine equipped with either mechanism without the other, as well as with both together.

It will be observed that the faces 83, 83, of the head of the securing lever 80 are beveled. When a tree is moved into operative 95 position the lug d^{10} contacts with one of the beveled faces 83 and forces the securing lever back against the pull of the spring 84 until the lug reaches the notch in the lever head after which the lever moves quickly 100 forward to secure the tree against further movement or reverse movement. The spring plungers 66 and the inclined faces 83 of the 105 spring-actuated securing lever act as buffers coöperating to check the movement of the parts carried by the rockshaft and to prevent excessive jarring of the machine.

As has been suggested, it is at times desirable to employ one tree only, either the 110 left or the right one, for expanding two or more shoes in succession, and at such times it is not advantageous to have the tree moved to and from position to be operated upon by the actuating lever 40. I have 115 therefore so arranged the mechanisms for releasing the tree and for moving it aside that said mechanisms can be rendered inoperative at the will of the workman.

The carrier 102, as before stated, is pivotally connected to the lever 43 at one end, and its other end is suspended by the hanger 104. The arm 60 has a portion 61 extending beneath the carrier. When it is desired to use a single tree for several shoes in succession, the outer end of the carrier is detached from the hanger 104, and the carrier is allowed to drop into the position in which it is shown in Fig. 6, where it rests upon the end portion 61 of the arm 60, which in 125 130

turn rests on the outer portion of the cam plate 50, as shown. When the carrier is in this position the tripping device 100 is out of reach of the releasing lever 80, and the 5 cam operating arm 60 is tilted so that the roll 64 will not contact with the cam 52 and the rockshaft 9 is therefore not turned by the movement of the lever 43. The tree which is in operative position will then be 10 expanded and locked in expanded condition by a forward movement of the head of the actuator 40 away from the workman,—that is, to the right as seen in the drawings,—and when the actuator is reversely moved the 15 stop or abutment 35 will contact with the face 31 of the latch 24 to unlock the tree and permit it to be collapsed.

So far as I am aware of the state of the art, I am the first to provide a treeing machine with means for presenting a tree to the workman and for moving it away from him after his operation on it has been completed. I am also the first to provide a treeing machine having a plurality of trees with 20 means for moving the trees to present them successively at a given point in the machine, as for instance to the actuator which causes the expansion of the trees. These features 25 I regard as of great importance and I desire to claim them broadly. It is further new with me to equip a machine which has a manually controlled device, with connections between said device and the trees whereby the trees will be automatically 30 moved to present them in succession at a given point.

The operation of the machine is as follows:—A shoe is applied to a tree when it is in the position in which the right hand tree 40 is shown in Fig. 4, said tree being contracted. The workman then depresses the arm 43^a of the lever 43 until the lug 47 thereon has engaged the catch 48. This movement of the lever 43 causes the lever 40 to engage 45 the lug 21 and move the rod d^4 toward the right to expand the tree within the shoe. The latch 24 engages the shoulder 23 of the lug 21 when the tree has been expanded to the desired condition, and thereafter 50 locks the tree in such expanded condition until the latch is released. The workman then performs the customary rubbing of the shoe to remove therefrom the wrinkles and creases. This rubbing usually produces 55 some expansion of the shoe, and the strong spring 15, which has been somewhat compressed when the tree was expanded, exerts a constant pull upon the rod d^4 and causes said tree to be further expanded to take up 60 any slack in the shoe produced by the treeing operation. When the treeing operation has been finished and, if desired, a coat of dressing has been applied, the workman with his foot touches the foot-piece 43^x of 65 the bell-crank lever moving said lever

slightly to his left as he stands in front of the machine and thereby disengages the lug 47 from the catch 48 on the frame to permit the lever 43 to be restored to normal position by the returning spring 70. The lever 43 in returning to normal position actuates the tripping device 100 which releases the securing lever 80 and permits the spring plungers 66 which are in engagement with the lug 56 of the cam plate to start the rockshaft and thus move the tree and carry its lug d^{10} away from the securing lever 80. The impulse given by the plunger 66 will turn the rockshaft far enough to bring the next tree to be operated upon within reach 75 of the workman so that he could complete its movement manually without leaving his place. If the machine is equipped with the cam operating arm 60, however, the roll 64 thereon engages one of the cam surfaces 52 80 immediately after the tree has been released, and accelerates the movement of the rockshaft so that the tree next to be operated upon is carried against the inclined face 83 of the securing lever, which it presses back 85 until the lug d^{10} reaches the notch in the head of the lever, when it comes to rest. As said tree comes into position one of the plungers 66 is engaged by the lug 56 on the cam plate and is pressed back, said plunger acting as 90 a buffer to check the movement of the rockshaft. If the abutment 33 is in its operative position it is engaged by the face 29 of the latch head and the tree is automatically 95 unlocked. If a further treeing operation is to be performed on the shoe carried 100 by said returned tree, or a second coat of dressing is to be applied, the abutment 33 will have been rendered inoperative by adjusting it below the head of the lever 40 105 and will not be in position to engage the latch and the tree will therefore remain expanded.

When the further operation is completed, if it is desired to remove the shoe from the 110 tree, the bell-crank lever 43 will be depressed to move the actuator 40 far enough forward to bring the abutment 33 into contact with the beveled face 30 of the latch and turn said latch and unlock the tree so that it can 115 be collapsed. If the shoe is not to be removed from the tree at this time but requires to stand longer for permitting the dressing to dry or for any other reason, the lever 43 is depressed the full extent of 120 its stroke and the actuator 40 engages the lug 21 of the tree immediately after the latch has been turned by the abutment 33 so that the tree is not collapsed to an appreciable extent and the latch reengages the lug 21 to lock the tree again. In this manner the tree can be presented two or more times, as may be desired, in position to have the shoe operated upon.

By the expression "treeing mechanism" 130

I mean to include any mechanism for stretching or shaping the shoe, such, for instance, as mechanism for expanding the tree for filling and shaping the shoe carried thereby; and by the expression "means for operating upon the tree" I mean to include any means for actuating the tree to cause it to fill, shape, or expand the shoe or to cause it to contract for permitting the removal of the shoe therefrom. If it is desired to tree two or more shoes successively on one tree, the carrier 102 will be disengaged from the hanger 104 and allowed to rest on the tail 61 of the arm 60 in which position the tripping device 100 and the cam operating arm 60 will both be rendered inoperative. With the parts in this position when the spring 70 is allowed to return the lever 43 and actuator 40 to normal position, the abutment 20 35 on the actuator will engage the beveled face 31 of the latch head 28 and unlock the tree so that it may be immediately collapsed and the shoe removed therefrom.

Having thus described my invention what 25 I claim is:

1. A treeing machine comprising a tree arranged for movement toward and from a specified point and yieldingly acting means for moving the tree to present it at said 30 specified point.

2. A treeing machine comprising a tree, means for operating upon the tree, and means for removing said tree from the position occupied by it while being operated 35 upon, said latter means being adapted to be rendered operative or inoperative at the will of the workman.

3. A treeing machine comprising a tree and a manually controlled treeing mechanism, and connections between said tree and said mechanism for moving said tree into 40 operative position.

4. In a treeing machine, a plurality of trees, means for operating upon the trees one 45 at a time and mechanism acting yieldingly to present the trees successively in position to be operated upon.

5. A treeing machine, comprising a plurality of trees, means for operating upon the 50 trees, and mechanism for moving said trees to present them successively in position to be operated upon, said mechanism being constructed and arranged to be rendered operative or inoperative at the will of the 55 workman.

6. A treeing machine comprising an expandable tree, and an actuating mechanism for expanding said tree, in combination with mechanism connecting said actuating 60 mechanism and said tree whereby the tree is automatically moved to present it to the actuating mechanism.

7. A treeing machine comprising a plurality of trees and a manually controlled 65 operating mechanism for said trees, in com-

bination with mechanism connecting said trees and said manually controlled operating mechanism whereby said trees are automatically moved to present them successively at a specified point in the machine. 70

8. A treeing machine comprising a plurality of expandable trees, mechanism for expanding said trees, said mechanism comprising a manually operated device, and connections between said trees and said device for 75 moving said trees successively into operative position with relation to said expanding mechanism.

9. In a treeing machine, a tree movable into and out of operative position, and 80 means for securing said tree in operative position, said means comprising a device normally in position to hold the tree, actuating means for effecting the withdrawal of said holding device, and means under control of 85 the workman for rendering said actuating means operative.

10. In a treeing machine, a tree movable into and out of operative position, and 90 means for securing said tree in operative position, said means comprising a holding device arranged for movement toward and from position for securing the tree, actuating means constructed and arranged for effecting the momentary withdrawal of said 95 holding device, and means under control of the workman for rendering said actuating means operative.

11. In a treeing machine, a tree movable into and out of operative position, and 100 means for securing said tree in operative position, said securing means comprising a device normally in position to hold the tree, and means arranged to be rendered operative at the will of the workman for actuating said device to release the tree. 105

12. In a treeing machine, a tree movable into and out of operative position, and 110 means for securing said tree in operative position, said means comprising a movable locking device, and a tripping device arranged to be actuated in a path intersecting the path of movement of said locking device for momentarily withdrawing said locking device from engagement with the 115 tree.

13. In a treeing machine, a tree movable into and out of operative position, and 120 means for securing said tree in operative position, said means comprising a lever yieldingly pressed toward operative position, and a tripping device adapted to engage an abutment on said lever and arranged to be reciprocated in a path intersecting the path in which the abutment moves when the lever is 125 turned, whereby the lever is engaged and rocked by the tripping device during a portion of the movement of the latter.

14. In a machine of the class described, a 130 tree, an actuator for expanding the tree

during one movement, said tree being movable into and out of operative relation to said actuator, means for retaining said tree in operative position, and means operated by the actuator during another movement for releasing the tree from its retaining means.

15. In a machine of the class described, a tree, an actuator for expanding the tree, 10 said tree being movable into and out of operative relation to said actuator, means normally operative for securing said tree in operative position, and means adapted to be rendered operative at the will of the workman for releasing said securing means automatically to permit the tree to be moved out of operative relation to the actuator.

16. In a treeing machine, a tree, a device for securing the tree in operative position, 20 an actuator for expanding the tree, and mechanism connected with said actuator and operated thereby for releasing the tree and moving it away from operative position.

17. In a treeing machine, a plurality of 25 expandible trees, and connected mechanism for expanding one of said trees and moving it aside and presenting another tree in position to be expanded, at a single operation of said mechanism.

30 18. In a treeing machine an arm adapted to support a tree, said arm being movable to and from an operative position, and means for securing said arm in operative position, said means comprising a lever provided with 35 stops for engaging opposite sides of the arm, beveled faces formed on the outer sides of the stops, and yielding means for holding the lever in operative position whereby it may be rocked by engagement of the arm 40 with said beveled faces to permit the arm to be positioned between the stops.

19. In a treeing machine, a tree movable to and from operative position, means for securing said tree in said position, automatic 45 means for giving said tree an initial movement away from said position when it is released from said securing means, and means for giving said tree a further movement away from operative position.

50 20. In a treeing machine, a plurality of movably supported trees, means for securing one of said trees in operative position at a time, and means for withdrawing the securing means to release said tree, combined 55 with automatic means for moving said tree away from operative position, and means acting on another tree for giving that tree an initial movement toward operative position.

60 21. In a treeing machine, a tree movable to and from an operative position, means for securing said tree in operative position, means for withdrawing said securing means, yieldingly actuated automatic means for 65 giving said tree an initial movement out of

the path of said securing means, and means for giving said tree a further movement away from operative position.

22. In a treeing machine, a plurality of 70 trees movable to occupy successively an operative position, and means for securing said trees in said operative position, combined with means for giving a tree which is in operative position a movement away therefrom, and means for causing another 75 tree to be moved into operative position.

23. In a treeing machine, the combination of a supporting frame, a head movable thereon carrying a plurality of trees, a lock for holding the head against movement with 80 a tree in working position, means for tripping the lock to permit the head to move, mechanism for moving the head to bring a tree into working position and provision whereby the locking device is freed from the 85 control of said tripping means to enable it again to lock the head when another tree is moved into working position.

24. In a treeing machine, an expandible 90 tree, an actuator for expanding said tree during one portion of its movement, means for locking said tree in expanded condition, and means for unlocking said tree by any subsequent similar movement of said actuator.

95 25. In a treeing machine, an expandible tree movable toward and from operative position, an actuator for expanding said tree during one of its movements, a latch for locking said tree in expanded condition, and means carried by the actuator and arranged to be adjusted into or out of operative position for moving said latch to release the tree during a subsequent movement of the actuator.

100 26. In a treeing machine, a movable head, trees carried by said head, a single actuator for causing the expansion of any one of said trees by one movement and for shifting said head to present another tree to the said actuator by another movement.

110 27. In a treeing machine, a head mounted on a rockshaft, trees carried by said head, a lever for causing the expansion of any one of said trees by a movement in one direction 115 and for actuating said rockshaft by a movement in the opposite direction, thereby to turn said head to present another tree to the lever.

120 28. In a treeing machine, a head, a tree supported on said head, an actuator, a cam for moving said head to present the tree intermittently in operative relation to the actuator, and connecting mechanism whereby the actuator alternately expands the tree 125 and turns the cam to move the tree from operative position.

130 29. In a treeing machine, a tree, actuating devices for expanding the tree, including a lever and a returning spring therefor, and

means for moving said tree out of operative relation to the actuating devices after it has been expanded, said means comprising a shaft to which the tree is connected, a cam also connected with the shaft and means whereby the cam is actuated by the lever returning spring.

30. In a treeing machine, a tree and means for moving it into and out of position to be operated upon, said means comprising a lever and means to actuate it, a cam connected with said tree and having a face inclined to the plane of movement of the lever, and a roll carried by the lever for engaging 15 said inclined face, whereby the cam is actuated to move the tree.

31. In a treeing machine, a tree, and means for moving it into and out of position to be operated upon, said means comprising 20 a cam connected with said tree and provided with two inclined faces, a lever, and a roll carried thereby, and means to actuate the lever for causing the roll to engage one or the other of said inclined faces to actuate the 25 cam and move the tree into or out of position to be operated upon.

32. In a treeing machine, the combination with an expandible tree, of a lever, and connections between said lever and the tree 30 whereby the tree is expanded during one stroke of the lever and during the reverse stroke of the lever is moved with relation to the position occupied by it while being expanded.

33. In a treeing machine, arms adapted to support trees, said arms being movable toward and from an operative position, and means for securing an arm in operative position, said means comprising stops adapted to 35 engage opposite sides of an arm and mounted on a movable support, combined with means for actuating said support to withdraw the stops simultaneously from the path of the arm to permit the arm to be 40 moved in either direction away from operative position.

34. In a treeing machine, a movable tree, a swinging lever formed at one end as a latch for securing the tree in fixed position, 50 and an actuator adapted to have operative connection with the other end of the lever for operating the latch to release the tree, said lever and actuator being arranged for relative movement to disconnect the actuator 55 from the lever during the operation of the actuator.

35. In a machine of the class described, a latch, and a reciprocating actuator arranged to have operative connection with the latch, 60 said parts being constructed and arranged for relative movement to interrupt the operative connection between the latch and the actuator during the stroke of the actuator, and means independent of the actuator for 65 returning the latch to its normal position.

36. In a machine of the class described, a latch, and a reciprocating actuator for operating the latch, one of said parts being arranged to move normally in a path at an angle to the path of movement of the other 70 part whereby they are automatically disconnected during the reciprocation of the actuator.

37. In a machine of the class described, a pivoted latch, a reciprocating actuator arranged to have operative connection with the latch, and means to advance the actuator, said latch and actuator being constructed and arranged so that the actuator moves 75 normally in a path to first operate the latch 80 and thereafter to interrupt the operative connection between the latch and actuator during the continued advance of the actuator.

38. In a machine of the class described, a swinging lever formed at one end as a latch, 85 and a reciprocating actuator arranged to have operative connection with the other end of the lever, said parts being constructed and arranged for relative movement to interrupt the operative connection between 90 the lever and the actuator during the stroke of the actuator, and means independent of the actuator for returning the lever to its normal position.

39. In a machine of the class described, a 95 swinging lever formed at one end as a latch, a reciprocating actuator arranged to have operative connection with the lever, and means for advancing the actuator in a path to engage the lever during a portion of its 100 movement and thereafter discontinue engagement with the lever during the remainder of its movement.

40. In a treeing machine, an expandible tree, an actuator for expanding said tree, 105 means for locking said tree in its expanded condition, said tree being movable while in its expended condition out of operative relation to said actuator, and means carried by the actuator for automatically unlocking said 110 tree to permit it to collapse when it is again moved into operative relation to said actuator.

41. In a treeing machine, an expandible tree, mechanism for expanding said tree, 115 said mechanism including a manually operated device, means for locking said tree in expanded condition, said tree being movable out of operative relation to said expanding mechanism while in its expanded 120 condition, and means for automatically unlocking said tree to permit it to collapse when it is again moved into operative relation to said expanding mechanism, the last mentioned means being connected with said 125 manually operated device to be moved thereby.

42. In a treeing machine, a plurality of trees, an expanding mechanism for expanding said trees one at a time, said mechanism 130

including a manually operated device, means for locking each tree in its expanded condition, each of said trees being movable while in expanded condition out of operative relation to said expanding mechanism, and means for automatically unlocking each tree to permit it to collapse when it is moved into operative relation to said expanding mechanism, the last mentioned means being connected with said manually operated device to be moved thereby.

43. In a treeing machine, a supporting frame, a head rotatable on said frame, a tree carried by said head, an expanding mechanism, said tree having an expanding rod and being arranged for movement toward and from said mechanism, a pivoted latch carried by said head, a spring operating on said latch to hold it in latching position, a projection operatively associated with the expanding rod of said tree and arranged to be engaged by said latch to hold the tree in expanded condition, and a tripping device arranged to trip said latch automatically to permit the tree to collapse when the tree is moved into operative relation to said expanding mechanism.

44. In a treeing machine, the combination of a supporting frame, a head movable thereon carrying a plurality of trees, and means under control of the operator acting yieldingly to move said head to bring a tree into working position.

45. In a treeing machine, the combination of a supporting frame, a head movable thereon carrying a plurality of trees, means for moving the head to bring a tree into work-

ing position and means acting yieldingly to arrest the movement of the head with a tree in working position.

46. In a treeing machine, the combination of a supporting frame, a head movable thereon carrying a plurality of trees, a turning member connected to said head and yieldingly actuated means co-operating with said member to move the head to bring a tree into working position and prevent sudden starting movements of the head.

47. In a treeing machine, the combination of a supporting frame, a head movable thereon carrying a plurality of trees, means for moving the head to bring a tree into working position and a device yielding in the direction of movement of the head to bring the head to rest with a tree in working position.

48. In a treeing machine, the combination of a supporting frame, a head movably mounted thereon carrying a plurality of trees, yieldingly acting means for moving said head to bring a tree into working position, a stop to arrest the motion of the head when a tree is moved into said position, and means controlled by the operator for tripping said stop and bringing said yieldingly acting means into operation.

In testimony whereof I have signed my name to the specification in the presence of two subscribing witnesses.

JOHN SEVERIN HANSEN.
